Louis C. Martin Inventor

Orde B. Billman Attorney

UNITED STATES PATENT OFFICE.

LOUIS C. MARTIN, OF WILLOUGHBY, OHIO.

MOLD-INSERT-FEEDING MECHANISM.

1,391,334.

Specification of Letters Patent. Patented Sept. 20, 1921.

Application filed December 29, 1920. Serial No. 433,767.

To all whom it may concern:

Be it known that I, LOUIS C. MARTIN, citizen of the United States, residing at Willoughby, in the county of Lake and State of Ohio, have invented certain new and useful Improvements in Mold-Insert-Feeding Mechanism, of which the following is a specification.

My invention relates to improvements in mold insert feeding mechanism adapted to carry and to feed in proper relative position within a mold cavity such inserts as it is desired to cast within the molded casting.

The present embodiment of this invention is particularly designed and adapted for use in supplying the small washer inserts upon the supporting studs of the mold cavities in the drag section of a flask preparatory to casting the ordinary rubber heels of commerce.

The primary object of the invention is to provide a generally improved insert holding and feeding mechanism adapted to carry a plurality of superposed inserts in proper relative positions with respect to the mold cavities and to automatically and simultaneously deposit the lowermost washer or insert upon the pins or studs in the respective heel or mold cavity.

With the above mentioned and other ends in view, the invention consists in the novel construction, arrangement and combination of parts, hereinafter described, illustrated in some of its embodiments in the accompanying drawing, and particularly pointed out in the appended claims.

Referring to the drawings, forming a part of this specification, Figure 1 is a top plan view of a drag section of a flask provided with the usual heel forming cavities and insert supporting studs.

Fig. 2, a side elevation of the same equipped with a device for feeding and depositing the mold washer inserts upon the supporting studs, the insert feeding and guiding members being unequipped with the inserts for the purpose of illustration.

Fig. 3, a top plan view of the same.

Fig. 4, a sectional view of the drag section, with a partial sectional view of the mechanism taken on line 4—4 of Fig. 3, the feeding, guiding and supporting members being equipped with washer inserts.

Fig. 5, a fragmentary sectional view of the same, the insert depositing and separating elements being in released position pre-

paratory to reengaging the superposed insert above the lowermost ones after the deposit of the latter on the shouldered portions of the insert supporting pins or studs in the heel cavity.

Fig. 6, a cross or transverse sectional view illustrating a modified form of insert feeding and guiding members together with a modified form of insert depositing and separating elements.

Fig. 7, a top plan view of the same.

Fig. 8, a sectional view taken on line 8—8 of Fig. 6.

Fig. 9 is a view of a washer.

Similar numerals of reference designate like parts throughout all the figures of the drawings.

The drag section 1, of the flask may be of any suitable and convenient form, and so likewise as to the mold cavities 1^a, and the inserts together with the means for supporting the latter in the mold cavity.

For the purpose of illustration and as showing one of the various applications of my invention, I have shown my device applied to the drag section of a heel molding and vulcanizing flask, and hence the mold cavities 1^a, are in the specific form of heel forming and vulcanizing cavities provided with the usual washer insert supporting studs 1^b. It will be seen that the studs 1^b, are provided with supporting shoulders and with reduced stem or pin portion 1^c.

Referring now to the improved insert holding and feeding mechanism to which this invention particularly relates, it will be seen that a suitable support or frame 2, is provided, said frame 2, in the present instance, being provided with openings 2^a, to receive and contain the insert feeding, guiding and depositing mechanism hereinafter referred to.

As a means of properly positioning and adjusting the support 2, and the respective insert feeding and depositing devices with respect to the insert supporting studs 1^b, the support or frame 2, may be provided with adjusting legs or supports 3, having their lower ends adapted to fit into suitable openings 1^a, in the drag section of the flask.

As a means of providing suitable bearing supports for the various insert supporting, feeding and depositing mechanism, herein-after described, the frame or support 2, may be provided with longitudinally extending bars 4, provided with attaching screws 4^a,

and arranged, in the present instance, on opposite sides of the openings 2^a, in the frame 2.

As a means of properly holding, positioning and feeding a supply of inserts in the 5 specific form of washer inserts 5, in proper relative position and immediately above the pin portions 1^c, of the supporting studs 1^b, suitable insert feeding and guiding members 6, are provided, said feeding and guiding 10 members 6, being mounted, in the present instance, upon cross supporting members 7.

In the form shown in Figs. 1 to 5, inclusive, of the drawings, the insert feeding 15 and guiding members 6, are in the specific form of wire or guide members adapted to extend through the openings within the washer inserts 5, and are supported directly in the cross members 7, of the support 2, 20 formed by the openings 2^a, while in the form shown in Figs. 6 to 8 of the drawings the insert feeding and guiding members 6, are in the specific form of tubes attached directly to the separate cross members 7^a, 25 which also support the insert engaging, releasing and reengaging elements hereinafter referred to.

As a means of vertically supporting the 30 inserts 5, in their superposed relation on the feed and guide members 6, the cross supporting members 7^a, are provided with depending movable elements 8, extending downwardly at the sides of the guide members 6, said elements 8, in the present instance, being in the specific form of spring 35 arms or tongues secured to the cross members 7^a, by means of the attaching elements or screws 8^a. The lower or free ends of the elements 8, are provided with insert supporting and separating points or flanges 8^b, 40 said points 8^b, normally acting to engage at the side of the lowermost washer insert 5, in supporting the latter and the superposed inserts preparatory to dropping the 45 column over the pin portions 1^c, of the studs, as shown most clearly in Fig. 4 of the drawing.

As a means of simultaneously moving or actuating the insert dropping and separating elements 8, the bearing bars 4, are provided with suitable openings adapted to receive and contain a plurality of rock shafts 9, the latter being provided at their ends with crank members 10, the free ends of the 55 cranks 10, being connected to a shifting bar 11, leading to an operating lever 12, the latter being connected to a bearing bracket 13, on the end of the support or frame 2.

In view of the tubular form of the feeding and guiding members 6, shown in Figs. 60 to 8, inclusive, of the drawings and the fact that such guiding members 6, are mounted directly on the separate cross supporting members 7^a, which also support the 65 insert depositing elements 8, the rock shafts

are in the specific form of stub shafts 9^a, and the links or shifting bars 11, are connected to the cross bar 12^a, carried by the operating lever 12.

In such tubular form of feed or guide elements 6, two oppositely arranged elements 8, are provided, the lower ends of the feeding and guiding tubular members 6, being provided with oppositely arranged notched recesses 6^a, to receive the points or flanges 75 8^b, which support the opposite edges of the lowermost washer insert before depositing, and for separating the latter from the superposed pile when the elements 8, are returned to their original positions by the 80 return movement of the lever 12, and shifting bars 11.

In the form shown in Figs. 6 to 8, inclusive, of the drawings, the stub shafts 9^a are provided with oppositely disposed cam 85 or pin elements 9^b, which wipe against the base portions of the spring or movable elements 8, to reciprocate the latter in first depositing the lowermost washer insert, then returning and reengaging the washer 90 insert immediately above the one deposited on the shoulder portion of the stud 1^b, and then supporting the stack or column of washer inserts until again brought into action for repeating the automatic discharge 95 of the next lowermost washer insert for loading up another series of heel forming cavities with such inserts.

Having thus described some of the embodiments of my invention, without having attempted to set forth all the forms in which it may be made, or all the modes of its use, what I claim and desire to secure by Letters Patent, is,—

1. In a mold insert feeding device, an insert feeding and guiding member vertically supported above the mold cavity and carrying a plurality of superposed inserts, a movable element at one side of said member provided with an insert supporting, depositing 105 and separating portion, and means for throwing said depositing and separating portion into and out of engagement with said inserts.

2. In a device for feeding inserts into a 115 mold cavity, a vertically arranged guide member having its lower end terminating in such cavity and supporting a plurality of inserts, and means for supporting said inserts from beneath the lowermost member 120 and for reengaging said inserts immediately above the insert deposited.

3. In a device for feeding inserts, a mold cavity, a guide member having its lower end terminating in such mold cavity, a plurality of inserts, supported on said guide member, and means on the latter for supporting and depositing said inserts and for reengaging said inserts immediately above the lowermost insert deposited. 130

4. In a feeding device for mold inserts, a feeding and guiding member arranged in a vertical position above the mold cavity to be filled, a reciprocatory member at the side of said guiding member provided with an insert supporting and separating element in coöperative relation to said guiding member, and means for operating said reciprocatory member.
5. In a feeding device for mold inserts, a vertical feeding member above the mold cavity to be filled, a reciprocatory member in coöperative relation to said guiding member having an insert supporting and separating element, and means for operating said reciprocatory member and insert supporting and separating element.
6. In a feeding device for mold inserts, including a drag section provided with a heel forming cavity having washer insert supporting studs on its bottom, a support adjustably mounted on said drag section and provided with insert separating and depositing elements communicating with said cavity, said guiding elements registering with said washer insert supporting studs to deposit the lowermost inserts thereon.
7. In a feeding device for mold inserts, including a drag section provided with a heel forming cavity having a plurality of washer insert supporting studs on its bottom, a support removably mounted on said drag section and provided with depending insert guiding and depositing elements, said guiding elements being adapted to register with said washer insert supporting studs whereby to deposit the lowermost inserts thereon.
8. In a feeding device for mold inserts, a support adapted to be suspended above the mold cavity of the drag section of the flask, insert feeding and guiding members arranged within said mold cavity, and insert separating and depositing members at the sides of said feeding and guiding members to deposit the lowermost inserts in said cavity when opened and to reengage and support the inserts immediately above the same when returned to their original positions.
9. In a feeding device for mold inserts, a support adjustably mounted above the flask and mold cavity, insert feeding and guiding members arranged on said support and extending within said mold cavity, and insert separating and depositing elements in coöperative relation to said feeding and guiding members arranged to deposit the lowermost inserts in said cavity when opened and to reengage and support the superposed inserts when returned to their original positions.
10. In a feeding device for mold inserts, a support adapted to be removably and adjustably mounted above the drag section of a molding flask, an insert feeding and guiding member carried by said support above the mold cavity and said drag section, superposed inserts carried by said feeding and guiding member, means for vertically supporting said inserts on said guiding member, and means for throwing said insert supporting means into and out of engagement with said superposed inserts to feed the latter from the lower end of said feeding and guiding member into said cavity.
11. In a feeding and positioning device for mold inserts including a drag section having mold cavities provided with insert supporting studs, a supporting frame removably mounted above said mold cavities, a series of insert feeding and guiding members carried by said frame and arranged above said studs in said mold cavities, insert supporting and feeding members at the sides of said insert guiding members adapted to vertically support inserts on the latter, rock shafts on said frame provided with cams adapted to engage said feeding members of said insert supporting members to deposit said superposed inserts, and means for returning said insert supporting members to reengage and support the inserts above the ones deposited on said studs.
12. In a device for feeding mold inserts, the combination with the drag section of a heel molding and vulcanizing flask provided with heel forming cavities having insert supporting studs therein; of a frame provided with depending insert feeding and guiding members positioned to register with said insert supporting studs, means for supporting superposed inserts on said feeding and guiding members, means for releasing said insert supporting means to drop said superposed inserts upon said insert supporting studs, and means for returning said insert supporting means into engagement with the first inserts above the lowermost inserts deposited and supported on said insert supporting studs.

In testimony whereof I have affixed my signature.

LOUIS C. MARTIN.
